UNITED STATES PATENT OFFICE.

JOSEF WERNER, OF MUNICH, GERMANY.

PENCIL-CASE.

1,041,926.

Specification of Letters Patent.

Patented Oct. 22, 1912.

Application filed April 28, 1910. Serial No. 558,254.

To all whom it may concern:

Be it known that I, JOSEF WERNER, citizen of Germany, residing at Munich, Bavaria, Germany, have invented certain new and useful Improvements in Pencil-Cases; and I do hereby declare the following to be a full, clear, and exact description of the invention, such as will enable others skilled in the art to which it appertains to make

10 and use the same.

In pencil-cases according to the prior art, in which the lead is adjusted by means of a member sliding on the case, the connection of the lead to said sliding member has 15 always been rigid; the consequence is that any shock to said member, for instance, when the case falls to the ground, will be transferred direct to the lead and frequently cause it to break. Further, the leads themselves are seldom perfectly straight and it was therefore heretofore found necessary to give the lead a certain amount of free play in the front aperture of the case, in order to prevent breakage of the lead when 20 adjusting; for purposes of writing and drawing it would however be very desirable for the lead to fit tightly into the front aperture of the case.

The present invention provides a pencil 30 case in which, on the one hand, all shocks are lessened and breakage of the lead thus avoided and on the other hand the lead is guided in the front aperture of the case without free play, fitting tightly into said 35 aperture without fear of crooked leads becoming broken when adjusted. These advantages are attained by interposing between the lead and the above-mentioned sliding member a more or less elastic or 40 flexible element, which imparts all axial movements of the adjustable sliding piece direct to the lead but at the same time weakens all outward shocks and also allows of a certain amount of lateral motion in the 45 case of crooked leads. This connecting element may consist of a coiled spring, or of a pin or bolt having at either end a ball and socket joint or similar connection.

Reference being had to the accompanying 50 drawing Figures 1 to 5 show a pencil case in which the connecting element between lead and sliding member consists of a coiled spring, Figs. 2 and 4 being views, Figs. 1 and 3 longitudinal sections and Fig. 5 a 55 cross-section. Fig. 6 is a longitudinal section through a pencil case in which a bar

with ball and socket joints forms the connecting element.

In the forms of construction shown in Figs. 1 to 5 the lead *a* is held at its rear end 60 by a coiled spring *d* adjustable in the longitudinal cavity *b* of the case *c*. The rear end of said coil-spring *d* is connected by means of an angular pin *e* or the like to the adjustable sliding member *f*.
65

In the form of construction according to Figs. 1 and 2 the connection between the pin *e* and the sliding member *f* is attained by means of a metal strip *l* projecting laterally through the longitudinal slit *g* of the 70 pencil case and fixed to said member *f*. The sliding member *f* can be fixed in position by a ring or collar *m*, axially adjustable on said member *f* and adapted to be pushed over small wedge-shaped projections *n* of 75 the lower and slitted portion of said member *f*.

In the form of construction according to Figs. 3, 4 and 5 the sliding member for adjusting the lead in the case is formed by a 80 strip of metal *f*, connected to the pin *e* and projecting through the slit *g* of the case *c*, being then bent around said case. In order to fix this sliding member in its position, a ring *h* having an aperture or recess *k*, corresponding to a wedge-shaped projection *i* of the sliding piece *f*, is adapted to be turned on said sliding member. By turning over the sides of the metal strip *f*, so 85 as to form a raised border *o*, the ring *h* 90 can be prevented from sliding off the part *f*.

The action of the device is similar in both forms of construction. In the first-mentioned (Figs. 1 and 2) the ring *m*, when pushed downward over the projections *n*, *n* 95 will press the lower slitted portion of the sliding member *f* against the case and thus secure it in position. In the second form of construction the turning of the ring *h* in 100 the direction of the arrow (Fig. 5) will have the same effect.

According to Fig. 6 a bar or bolt *p* is provided at either end with a ball and socket joint *q*, the lower joint connecting with the inwardly projecting part of the sliding member *f*. Instead of the ball and socket joints any other universal joint allowing of movement in any direction may be used.
105

If necessary, the sliding member in all the above-mentioned forms of construction 110 may be provided with concentric rings or ribs in order to increase the spring action

and the friction between said sliding member and the case, and thus to facilitate its secure locking in position. The parts *o* shown in the drawing may, for instance, be adapted 5 to form such ribs.

The lead *a* may consist of any desired material such as graphite, charcoal, chalk, crayon, copying-ink or the like.

What I claim as my invention and desire 10 to secure by Letters Patent is:

1. A device of the character described comprising a longitudinally bored case having a lateral slot therein, a lead contained in the bored case, means for moving the 15 lead including a member passing through the slot in the case, and a laterally yieldable resilient element interposed between the lead and said member, one end of said resilient element engaging the lead and the other end 20 thereof engaging the member passing through the slot in the case, the part of said resilient element intermediate its ends being capable of free lateral distortion, and the diameter of the bore in said case being 25 greater than the diameter of either said lead or said resilient element.

2. A device of the character described, comprising a longitudinally bored case having a lateral slot therein, a lead movable in 30 said case, a sliding member encircling said case and having a projection extending through the lateral slot into the case, said projection being adapted to move the lead in the case; and a laterally yieldable resilient 35 element having one end engaging the lead and the other end engaging said projection, the part of said resilient element intermediate its ends being capable of free lateral distortion, and the diameter of the bore in said 40 case being greater than the diameter of either said lead or said resilient element.

3. A device of the character described comprising a longitudinally bored case having a lateral slot therein, a lead movable in 45 said case, means for moving the lead comprising a sliding member having a projection extending through the lateral slot in the case, a coiled spring having one end en-

gaging said lead, and a pin connecting the other end of the coiled spring with said projection, the portion of said coiled spring intermediate its ends being capable of free lateral distortion, and the diameter of the bore in said case being greater than the diameter of either said lead or said coiled 55 spring.

4. A device of the character described comprising a longitudinally bored case having a lateral slot therein, a lead movable in said case, means for moving the lead comprising a sliding member having a projection extending through the lateral slot in the case, a laterally yieldable resilient element having one of its ends engaging the end of the lead and its other end engaging 60 said projection, the part of said resilient element intermediate its ends being capable of free lateral distortion, and means for locking 65 said projection in adjusted position, the diameter of the bore in the case being 70 greater than the diameter of either said lead or said resilient element.

5. A device of the character described, comprising a case having a longitudinal bore one end of which is exactly of a diameter to 75 retain a lead without play, said case having a lateral slot in the wall thereof, a laterally yieldable resilient element connected at one end to one end of the lead, the diameter of the bore in the case at points other than the said 80 end thereof being greater than the diameter of either said lead or said resilient element, means for longitudinally moving the lead, said means being connected to the end of the resilient element opposite that to which the 85 lead is connected, a projection on the lead moving means, and an apertured member adapted to be moved into engagement with said projection to retain the lead moving means in adjusted position.

In testimony whereof I hereunto affix my signature in the presence of two witnesses.

JOSEF WERNER.
